US00D839969S

(12) **United States Design Patent** (10) Patent No.: **US D839,969 S**
(45) Date of Patent: ** Feb. 5, 2019

(54) **CONTROLLER**

- (71) Applicant: **SZ DJI Technology Co., Ltd.**, Shenzhen (CN)
- (72) Inventors: **Min Kim**, Shenzhen (CN); **Haibin Zheng**, Shenzhen (CN)
- (73) Assignee: **SZ DJI Technology Co., Ltd.**, Shenzhen (CN)

(**) Term: **15 Years**

(21) Appl. No.: **29/590,870**

(22) Filed: **Jan. 13, 2017**

Related U.S. Application Data

- (63) Continuation of application No. 29/564,618, filed on May 13, 2016.

(57) **CLAIM**

The ornamental design for a controller, as shown and described.

DESCRIPTION

FIG. 1 is a bottom front perspective view of a controller showing the claimed design;

FIG. 2 is a top rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the figures show portions of the controller that form no part of the claimed design.

1 Claim, 7 Drawing Sheets
